CLAIM

The ornamental design for an adjustable support stand for reading material, as shown and described.

DESCRIPTION

FIG. 1 is a top, left front perspective view of an adjustable support stand for reading material showing my new design;

FIG. 2 is a left side elevational view thereof;

FIG. 3 is a rear elevational view thereof;

FIG. 4 is a top plan view thereof; and,

FIG. 5 is a right side elevational view thereof.

The bottom of the article is conventional in appearance.

FIG. 1

FIG. 2

FIG. 5

FIG. 4

FIG. 3
